UNITED STATES PATENT OFFICE.

THOMAS T. RODGERS, MARC A. GIBLIN, FRANCIS K. MOORE, AND GEORGE T. MOORE, OF MILWAUKEE, WISCONSIN, ASSIGNORS TO RODGERS RADIO CORPORATION, OF WEST ALLIS, WISCONSIN, A CORPORATION OF WISCONSIN.

VARIABLE CAPACITOR.

Application filed September 24, 1924. Serial No. 739,490.

Our invention has reference, in its broad aspect, to improvements in radio receiving apparatus of the type exemplified by multiple stage radio frequency amplification, and more particularly it is our purpose to provide a receiving apparatus of this character which may be tuned by the manipulation of a single medium.

In our co-pending application Serial Number 739,491, filed September 24th, 1924, for improvements in condensers, we define particularly the construction of a unique condenser apparatus embodying condenser units having a common operating medium; in our present application, however, we extend the concept of the above identified application, by defining the combination with a multiple condenser assembly, means whereby such condensers are mounted, insulated 20 each from the others, and manipulated.

In the present embodiment of our invention we provide means whereby all of the stages of radio frequency amplification may be simultaneously tuned through the medium of a common instrumentality. Heretofore it has been proposed to simultaneously tune the respective stages of radio frequency by mounting the rotors of conventional multiple plate rotary condensers upon a common shaft, but this has been found impractical for the reason that the slightest inaccuracy, distortion, imperfection or the like renders the system inoperative. We have found, on the other hand, that by utilizing air dielectric condensers having two opposed surfaces that the respective condensers for the several stages may be tuned simultaneously by altering the dielectric distance between the surfaces by equal increments. Furthermore, by combining in each stage of amplification a shielded magnetically balanced coil, such for instance as the conventional Figure 8 coil, and one of the type of condensers before mentioned, all 45 of the disadvantages of conventional systems of neutralized radio frequency are eliminated and a greatly improved and highly simplified radio receiving apparatus attained.

50 The particular elements of our radio receiving assembly employed to accomplish the above and other objects attributed to it will be hereinafter more fully described

in detail and specifically pointed out in the claims appended hereunto and forming a part of this specification.

In the accompanying drawings wherein we have illustrated one of the preferred embodiments of our invention:

Figure 1 is an elevation of the assembly partly in section,

Figure 2 is a detail of our recording and locking mechanism, and

Figure 3 is a detail view, partly in section, of the detector unit and means for holding our operating shaft in alignment.

Like characters of reference designate like or similar parts throughout the several views of the drawings, in which:

A designates generally any desired form of cabinet in which our receiving apparatus may be mounted, and B the top thereof. Suspended vertically from the top B of the cabinet is a frame generally designated by C which is formed with a transverse plate (1) having a central opening (2) and pins (3) which bear against the under side of the top B to hold the plate and top securely and rigidly together when the retaining screws (4) are set. The top B is also formed with a central opening registering with the opening (2) in the plate and within which extends the sleeve portion (5) of a disk (6). Suspended from the plate (1) of the frame are a plurality (preferably four) of vertical sectional rods (7), which are removably secured to the plate by studs (8); said rods and plate constituting the retaining elements of our receiving assembly. The disk (6) is disposed to rotate freely on the top and is provided with a suitable handle (9) for facilitating manipulation of the same. Beneath the top B and mounted for rotation with the sleeve (5) is a dial (10) the graduations thereon being arranged to pass beneath the peep opening (11) formed in the top for visible inspection. Furthermore, the dial (10) is provided with a pin (12) on its periphery which engages, upon each revolution of the dial, with one of the slots (17) in the indicating disk (13) the purpose of which is to indicate, through another peep opening (14), the number of times the dial has been rotated.

The sleeve (5) is internally screw-threaded (preferably 48 to the inch) and is adapted

to receive the screw-threaded end of a vertically extending sectional shaft (15), rotation of which is prevented by means of a fixed arm (16) carried adjacent the lower end thereof and slidably engaging one of the rods (7) so that only axial movement of the rod is permitted. Thus, upon rotation of the sleeve (5) through the instrumentality of the disk (6) the shaft (15) is caused to move axially in a direction dependent of course upon the direction of rotation of the disk. However, in order to positively limit the distance in either direction in which the shaft (15) may be fed, we have provided an interval (18) of uninterrupted continuity in the disk (13) which is engaged by the pin (12) on the dial (10) whereby said member (13) is prevented from making more than one complete revolution in either direction. Manifestly the movement of the member (13) being controlled by the movement of the dial (10) which is fixed to the sleeve (5) an effective stop is provided. A suitable lock nut (19) may be mounted on the sleeve (5) to prevent creeping of the dial (10), or the dial may be keyed to the collar (5) if so desired. It will be understood that while we have described the frame C and shaft (15) as being vertically arranged it is entirely feasible and sometimes desirable to dispose the assembly with the frame and shaft at other angles, in which case the shaft will, of course, move in the manner indicated, namely, axially.

As has been indicated, the vertical frame rods (7) are sectionally formed, the sections being secured together by studs (20). Carried by the frame C are a plurality of relatively parallel, spaced insulating partitioning members (21), the same being secured to the frame by engaging portions thereof (in the present case the corners) between the meeting ends of each of the sections of the frame rods (7). According to the concept of our present invention the compartments formed in the frame by the respective partitions (21) are designed respectively to house the several stages of radio frequency amplification, and if desirable, also the detector stage.

Mounted on each of the insulating partitioning members (21) by means of screws (22) is a condenser grid plate (23), but the grid plates are each separated from the partitioning members by inherently resilient devices, such as soft rubber washers (24), thus by manipulating the screws (22) a fine degree of adjustment of the grid plates on the insulating partitioning members can be attained against the resiliency of the washers (24). The shaft (15) extends through each of the grid plates and partitioning members, but the openings (25) in the grid plates are of considerably greater diameter than

the shaft, and the peripheral edges thereof are beveled as shown for the purpose of reducing capacity.

As has been indicated the shaft (15) is sectional in formation, the respective sections thereof being connected by studs (26), and between each of the sections of the shaft is mounted a plate (27). As shown, one plate (27) is opposed to each of the grid plates (23), and upon movement of the shaft axially the plates (27) will be varied in equal increments with respect to the plates (23). Furthermore, the plates (27) are of less diameter than the plates (23), or vice versa, thereby compensating for any variation in axial alignment between the respective plates which would result in variation in capacity.

We have described above means whereby the grid plates may be separately adjusted through the medium of the screws and rubber washers (24) but instead of the grid plates we may adjust the plates (27) in the same manner by seating the washers against a backing flange of a collar mounted on the shaft (15); or for that matter we may arrange in the same way to adjust both plates, or we may utilize other means for individual adjustment although that just described seems the most practical for commercial purposes. The purpose of adjustment readily suggests itself inasmuch as it is essential that the opposed surfaces of the plates be parallel and the dielectric the same. In operation we accomplish the exceedingly important result of simultaneous tuning of all our condensers through the instrumentality of the common shaft (15), and to this end it is essential that we attain equal electrical capacities between the respective condensers regardless of the separation of the condenser surfaces.

In order to effectively maintain the alignment of the shaft (15), there is connected to the lower terminal ends of the frame rods (7) by means of bolts (28) the spider (29), through the central insulated bearing (30) of which the shaft (15) extends. Furthermore the section of the shaft (15) which is common to the lowermost compartment (housing the detector stage) is formed in two units, one of which, designated (31) is insulated by a hard rubber washer or other suitable means (32) from the remaining unit and attached thereto by a hard rubber collar or other suitable means (33). The inductance and capacity exemplified by the transformer and condenser unit of this last stage can be omitted by the substitution of a fixed radio frequency transformer of conventional type (not shown).

Each stage of radio frequency consists in the usual tube and transformer, but in lieu of the conventional variable condenser which must be tuned individually, we have

provided the aforementioned means whereby all condensers are tuned simultaneously, thereby greatly simplifying the types of radio frequency receiving sets now found on the market. However, in addition to the foregoing we have also provided means, as has been suggested, whereby inherent regeneration is neutralized or balanced in a manner not contemplated by other processes following out the principle of neutralized radio frequency. We substitute for all previously known neutralized radio frequency systems a shielded figure 8 transformer (D), having a frame (36), attaching members (43) and the usual binding posts (44). One is used for each stage. It is understood that our shield may be applied to any coil and not necessarily to the present specific embodiment. It may here be said that the transformers are usually tuned or adjusted but once, and that at the time the apparatus is assembled, thereafter all tuning is accomplished by the simultaneous manipulation of the condensers as has been described.

It is believed that the operation of our invention will be apparent from the foregoing description of its various parts, but it is desired to emphasize the fact that we have not only provided a receiving apparatus of the multiple stage radio frequency amplification type wherein inherent regeneration is neutralized without the use of the conventional condenser connected from the grid of one tube to the secondary winding of the next radio frequency transformer, but we have provided means whereby each stage is tuned simultaneously by the manipulation of a single dial. When the disk (8) is revolved the sleeve (5) feeds the shaft (15) axially which varies the dielectric between the respective condenser plates by equal increments thereby accomplishing not only accurate tuning but tuning of a high degree of selectivity.

While in the foregoing, there has been illustrated and described such combination and arrangement of elements as constitute the preferred embodiments of our invention, it is nevertheless desired to emphasize the fact that interpretation of the invention should only be conclusive when made in the light of the subjoined claims.

We claim:

1. Radio tuning apparatus, comprising a frame formed with insulating partitions each having an opening therein, an axially movable shaft extending through the openings in said partitions, a plurality of condenser units each having a fixed plate and a movable plate having the whole of one of

its surfaces opposed to the passive plate at all times, said movable plates being connected with the shaft for simultaneous movement to vary the distance between the plates of the respective condensers by equal increments, and means for independently adjusting said fixed plates.

2. In a radio tuning apparatus a plurality of condensers, one for each stage of radio frequency and one for the detector stage, said condensers each having a movable plate for varying the distance between the plates, axially movable means for adjusting said movable plates to vary the distance between the plates of all the condensers simultaneously and by equal increments, the portion of said condenser adjusting means common to the detector stage being insulated from the remaining portion, and means engaging said last named portion for maintaining said means in an aligned position.

3. In a radio tuning apparatus, a frame formed of a plurality of sections adapted to be connected together at their ends, a plurality of insulating plates, one adapted to be disposed between each of the sections and forming partitions dividing the frame into a plurality of compartments, an axially movable shaft extending from end to end of the frame through said partitions, a plurality of condensers, one plate of each condenser being carried by the shaft, the other plate of each of the several condensers being mounted on the respective insulating partitions, and means for adjusting said last mentioned plates independently with respect to the partitions for the purpose defined.

4. In a radio tuning apparatus a frame formed with insulating partitions, an axially movable shaft extending through said partitions, a plurality of condenser units each having a fixed plate and a movable plate, the fixed plate of each condenser being mounted on an insulating partition and provided with an opening through which the shaft is adapted to extend, each of said fixed plates being beveled about the opening therein, the movable plates being connected to the shaft for simultaneous adjustment with respect to the fixed plates to vary the distances between the plates by equal increments, and means for independently adjusting the fixed plates with respect to the partitions.

In testimony whereof we affix our signatures hereunto.
